UNITED STATES PATENT OFFICE.

HARVEY B. TROXELL, OF SEATTLE, WASHINGTON, ASSIGNOR TO HARRIS & TROXELL,
A FIRM CONSISTING OF IVAN HARRIS AND HARVEY B. TROXELL, OF SEATTLE,
WASHINGTON.

DESIGN FOR A LOUD-SPEAKER HORN.

Application filed July 7, 1927. Serial No. 22,683. Term of patent $3\frac{1}{2}$ years.

To all whom it may concern:

Be it known that I, HARVEY B. TROXELL, a citizen of the United States, residing at Seattle, in the county of King and State of Washington, have invented a new, original, and ornamental Design for Loud-Speaker Horns, of which the following is a specification, reference being had to the accompanying drawing, forming part thereof.

Figure 1 is a perspective front elevation of my loud speaker horn, showing my new design;

Figure 2 is a plan view thereof; and Figure 3 is a side elevation of the same.

My loud speaker is intended for use in homes, and is designed with the object of standing it in and fitting it within the corner of a room.

I claim:

The ornamental design of a loud speaker horn, as shown and described.

HARVEY B. TROXELL.
